UNITED STATES PATENT OFFICE.

JACOB S. HIBSCHMAN, OF STRAUSSTOWN, PENNSYLVANIA.

DESIGN FOR A WHIFFLETREE-RING SCREW.

40,731.

Specification for Design.

Patented June 14, 1910.

Application filed April 18, 1910. Serial No. 556,275. Term of patent 7 years.

To all whom it may concern:

Be it known that I, JACOB S. HIBSCHMAN, a citizen of the United States, residing at Strausstown, in the county of Berks and State of Pennsylvania, have invented a new, original, and ornamental Design for Whiffletree-Ring Screws, of which the following is a specification, reference being had to the accompanying drawings, forming a part thereof.

In the accompanying drawing:—Figure 1

is a front view of a whiffletree ring screw showing my new design. Fig. 2 is a side view thereof. Fig. 3 is an end view thereof.

I claim:—

The ornamental design for a whiffletree ring screw, as shown.

JACOB S. HIBSCHMAN.
